UNITED STATES PATENT OFFICE.

ARTHUR L. LEE, OF NEW YORK, N. Y., ASSIGNOR OF ONE-HALF TO GASTON LACOMME, OF BROOKLYN, NEW YORK.

DOOR-FASTENER.

No. 874,688.

Specification of Letters Patent.

Patented Dec. 24, 1907.

Application filed October 17, 1907. Serial No. 397,791.

To all whom it may concern:

Be it known that I, ARTHUR L. LEE, a citizen of the United States, residing at New York city, Brooklyn, county of Kings, State 5 of New York, have invented new and useful Improvements in Door-Fasteners, of which the following is a specification.

This invention relates to a pocket door fastener of simple construction which enables 10 travelers and others to effectively secure the door of their apartment against opening from without.

In the accompanying drawing: Figure 1 is a face view of my improved door fastener; 15 Fig. 2 a similar view, showing it in use, with the door and door-frame in section; Fig. 3 an end view of the fastener, showing it closed; Fig. 4 a longitudinal section on line 4—4, Fig. 2, and Fig. 5 an enlarged cross 20 section on line 5—5, Fig. 2.

The base of a resilient triangular bail 10 is divided at the center to form two axially opposed shanks 11, 12. Shank 11 is bent inward at its free end to form a lug 13, to which 25 is pivoted by pin 14, a hook 15 having beak 16. Shank 12 has a rounded end to constitute a spring-catch 17 which enters a recess 18 of hook 15, and thus holds the latter in position.

30 In use, the hook with its beak pointing upward or downward is placed against the door-frame 19 or door 20, the door is closed and then the hook is turned at right angles, so that beak 16 will enter frame 19. The

device being thus locked to the door-frame, 35 the door cannot be opened as the shank 11 extends partly across the same, (Fig. 2). To release the door, the fastener is turned back until beak 16 becomes disengaged from frame 19, when the device may be readily 40 withdrawn.

If the fastener is to be carried in the pocket, hook 15 is swung into bail 10, so that the length of the device is correspondingly reduced. As hook 15 is disconnected from 45 shank 12, a clearance between these two parts may be readily formed for the purpose of utilizing the bail as a key-ring.

I claim:

1. In a door fastener, a resilient bail having 50 a pair of axially opposed shanks, combined with a hook pivoted to one of said shanks and engaged by the other shank, substantially as specified.

2. In a door fastener, a resilient triangular bail having a pair of axially opposed shanks, of which one terminates in a lug and the other terminates in a catch, combined with a hook pivoted to the lug and having a recess adapted to be engaged by the catch, substantially as specified.

Signed by me at New York city, (Manhattan,) N. Y., this 16th day of October, 1907.

ARTHUR L. LEE.
